UNITED STATES PATENT OFFICE.

LEWIS C. BAYLES, OF EASTON, PENNSYLVANIA. ASSIGNOR TO INGERSOLL-RAND COMPANY, OF JERSEY CITY, NEW JERSEY, A CORPORATION OF NEW JERSEY.

STEERING APPARATUS.

Application filed November 3, 1925. Serial No. 66,514.

To all whom it may concern:

Be it known that I, LEWIS C. BAYLES, a citizen of the United States, and a resident of Easton, in the county of Northampton and State of Pennsylvania, have invented a certain Steering Apparatus, of which the following is a specification accompanied by drawings.

This invention relates to steering apparatus, and although the features of the invention are capable of general application they possess special advantages when applied to the steering apparatus of boats or ships.

The objects of the invention are to render steering apparatus of boats easily operable and controllable; to enable the rudder to be operated by motive fluid by relatively inexpensive apparatus; and to enable the helmsman to control the rudder so that it will assume any desired predetermined position.

The invention will be more clearly understood by reference to the following description taken in conjunction with the drawing which includes,

Figure 1, a perspective view of a steering apparatus constructed in accordance with the practice of the invention, the view being partly in longitudinal section to show the interior construction of the parts,

Figure 2, a section of the throttle valve taken along the line 2—2 of Figure 1 looking in the direction of the arrows,

Figure 3, a vertical cross section of the fluid actuated motor for operating the rudder,

Figure 4, a cross section of the throttle taken along the line 4—4 of Figure 3 looking in the direction of the arrows,

Figure 5, a view partly diagrammatic and a cross section through the throttle valve similar to Figure 2 to illustrate the manner in which the throttle valve is controlled by the movement of the rudder,

Figure 6, a view partly diagrammatic and partly a section through the throttle valve showing the valve operated to produce a predetermined deflection of the rudder, and

Figure 7, a view partly diagrammatic and partly of cross section of the throttle valve the manner in which the throttle valve is closed automatically when the rudder has reached its predetermined position.

Referring to the drawings, the invention is shown as applied and combined with a

steering equipment of the type usually found on smaller boats and ships. A rudder A is adapted to be swung or inclined in one direction or the other by means of a drum B provided with a pair of ropes C and D passing over guiding pulleys E and attached to a cross arm F rigidly mounted on the rudder A. The drum B is suitably keyed or otherwise attached to a shaft G supported by suitable bearing standards H and may be manually rotated by a steering wheel J fixed to one end of the shaft G. The bearing standards are mounted on the deck K and the ropes C and D pass through the deck to the cross arm F. Such an apparatus is difficult to manage manually on a large ship or during maneuvering. This invention is adapted to relieve the operator of the greater part of the labor in steering the ship or boat.

To this end there is provided a fluid actuated motor L driving a shaft O through spiral gears P and Q. A pulley R on the shaft O drives a belt S passing over a pulley T preferably larger than the pulley R and mounted on the drum B. As shown in Figure 3 the motor L may be of the gear type and is reversible so that the drum B may be driven in either direction correspondingly swinging the rudder A to either side.

The construction of the motor L and its controlling throttle valve is shown in detail in Figures 2, 3 and 4. The motor L comprises a pair of mutually engaging gears U and V adapted to rotate in an elongated chamber W having semi-cylindrical end faces X and Y providing a relatively close fitting surface for the ends of the teeth of the gears U and V to slide on. Exhaust ports for the motive fluid supplied to actuate the gears U and V escapes through end passages Z and b to atmosphere. Motive fluid for actuating the gears U and V is supplied through one of a pair of passages c and d depending upon the direction in which it is desired to rotate the gears U and V. The gear V is in this instance the driving gear and is provided with a shaft e upon which the spiral gear P is mounted. It is understood that when the passage c is provided with motive fluid for driving the gears U and V the passage d is disconnected from the supply of motive fluid and vice versa.

A throttle valve for controlling the supply of motive fluid to either the passage c or the passage d comprises the rotary plug 110

105

valve f provided with a relatively long shank g extending upwardly from the motor to a convenient position to be turned by the operator and is provided at the end of the shank g with a manually operable handle h . A sleeve j is also provided and is adapted to cooperate with the valve f in controlling the supply of motive fluid to the motor L . The sleeve j is rotatable within the outer casing k to which a suitable supply pipe o for motive fluid is adapted to be attached. The valve f is provided with two longitudinal passages p and q communicating through a bushing r by means of grooves s and ports t with passages u and v respectively leading to passages c and d respectively.

Normally the throttle valve f is not adapted to rotate through an angle of more than 180° and in any such position the passage p is constantly in communication with the passage c and likewise the passage q is constantly connected with the passage d . Assuming that the rotary sleeve j remains stationary and in its straight forward position as shown in Figure 2 a turning of the throttle valve f to the left permits motive fluid to enter from the supply pipe o through a reduced portion w on the periphery of the sleeve j through a port x into the interior of the sleeve, through a reduced portion y on the periphery of the throttle valve f and a port z to the passage p , and thence to the passage c to actuate the gears U and V . This causes rotation of the drum B and a swinging of the rudder A to the left which will be noted is the direction in which the handle h is turned. Likewise a turning of the handle h to the right causes motive fluid to enter the reduced portion z and through a port 3 to the passages q and d , causing rotation of the gears U and V in a direction opposite to that before described, and turns the drum B in a direction causing the rudder to swing to the right, which it will be noted is the direction in which the handle h has in this case been turned.

Means are provided to stop the motor L , and consequently the swinging of the rudder A at any predetermined or desired position without manipulation of the handle h beyond a first setting thereof. To this end the sleeve j is rotated in accordance with the movement of the rudder A and by means of a sprocket 4 driving a length of chain attached at its ends to flexible cords 6 which in turn are attached to a length of chain 7 passing over a sprocket 8 suitably mounted on the end of the rotatable sleeve j as by means of a key 9 .

Thus when the rudder A swings in either direction as the case may be by being actuated by the drum B the sprocket 4 through its above described connections rotates the sprocket 8 borne by the sleeve j so that the sleeve j follows the movement of the rudder

A. The motor L therefore continues to run until the port x of the sleeve j is cut off or moved out of communication with the reduced portions y or z depending upon the direction of swinging of the rudder A .

70

This operation is more clearly illustrated in Figures 5, 6 and 7. In Figure 5 the handle h is in the position corresponding to the straight forward position of the rudder A . Assuming that it is desired to turn the rudder A to the left as for instance approximately 45° the handle h is turned that amount toward the left which opens the throttle valve permitting the supply of motive fluid from the pipe o through the port x in the sleeve j into the reduced portion y of the throttle valve f and thence into the passage p , whereupon the motive fluid causes the motor L to operate turning the drum B and swinging the rudder A to the left. The motor L continues to operate until the turning of the drum B and the swinging of the rudder A , through the connections associated with the sprockets 4 and 8 , turn the sleeve j to the position shown in Figure 7 at which the port x is closed by the valve f . In this position the rudder A is substantially parallel to the handle h . It is assumed that in this case the proportions of the cross arm F to the diameter of the drum B will produce the requisite turning of the sleeve j to cause the handle h and the rudder A to assume parallel positions. In any case a given degree of turning of the handle h will result in a proportionate movement of the rudder A . It is not necessary that the relative displacement of the two be the same.

90

To prevent the leakage of motive fluid along the shank g of the throttle valve f a stuffing gland 10 is provided about the shank g in the end of the sleeve j .

100

I claim:

1. Steering apparatus comprising a steering element, a fluid actuated motor for operating said steering element, a throttle valve for said fluid actuated motor including a manually rotatable control valve, a casing, and a sleeve interposed between said casing and said manually rotatable valve adapted to be automatically rotated by the steering element to close said valve.

110

2. A steering apparatus comprising a steering element, a fluid actuated motor for operating said steering element, a throttle valve for said fluid actuated motor including a manually rotatable control valve, a casing for said valve, and means movable independently of the valve and automatically operable by the steering element to cut off the supply of motive fluid to said valve.

120

3. A steering apparatus comprising a steering element, a fluid actuated motor for operating said steering element, a throttle valve for said fluid actuated motor including a manually rotatable control valve, a sta-

130

tionary casing for said valve and a sleeve ported to cooperate with said valve and automatically operable by the steering element to cut off the supply of motive fluid to said

5 valve.

4. A steering apparatus comprising a steering element, a fluid actuated motor for operating said steering element, a throttle valve for said fluid actuated motor includ-

ing a manually rotatable control valve, a 10 stationary casing for said valve and a rotatable sleeve ported to cooperate with said valve and automatically operable by the steering element to cut off the supply of motive fluid to said valve.

In testimony whereof I have signed this specification.

LEWIS C. BAYLES.
